COMPRESSION APPARATUS

Martin G. Sateren, West Springfield, Mass., assignor to Westinghouse Electric & Manufacturing Company, East Pittsburgh, Pa., a corporation of Pennsylvania

Application November 30, 1935, Serial No. 52,375
Renewed December 21, 1938

5 Claims. (Cl. 230—58)

My invention relates to compression apparatus, and particularly to compression apparatus of the type wherein a motor and compressor are enclosed in a hermetically-sealed casing.

5 It is an object of my invention to provide a hermetically-sealed motor compressor unit of improved design which is inexpensive to manufacture and which operates at high efficiency.

10 It is another object of my invention to effect lubrication and cooling of a hermetically-sealed motor-compressor unit by circulating lubricant between various parts of the apparatus.

15 It is a further object of my invention to provide an improved suspension for a sealed motor and compressor which damps vibrations from the unit, and at the same time to effectively cool the motor-compressor unit.

20 These and other objects are effected by my invention as will be apparent from the following description and claims taken in connection with the accompanying drawings, forming a part of this application, in which:

Fig. 1 is a vertical sectional view of my improved hermetically-sealed motor-compressor unit;

25 Fig. 2 is a view, partly in section, of my motor-compressor unit with portions of the enclosing casing removed;

30 Fig. 3 is a sectional view of the motor-compressor unit taken on the line III—III of Fig. 1, with the baffle plate removed;

Fig. 4 is a sectional view of the motor-compressor unit taken on line IV—IV of Fig. 2; and,

35 Fig. 5 is a detail plan view of the lubricant distributor disposed adjacent the top of the sealed casing of the motor-compressor unit.

Referring to the drawings for a detailed description of my invention, the sealed motor-compressor unit generally designated at 11 is particularly adaptable for use with refrigeration apparatus wherein a refrigerant is compressed, condensed and evaporated in a repeated cycle.

40 A sealed casing 12 encloses a motor and a compressor, generally indicated at 13 and 14, respectively. The casing 12 is formed from two drawn steel cup-shaped members 15 and 16 which are welded together at 17. A backing plate 9 is disposed peripherally of the welded joint 17 to prevent the welding arc from entering the interior of the casing 12 and damaging the equipment disposed therein. The cup-shaped members 15 and 16 are of sufficient extent that the weld 17 and portions of the members 15 and 16 may be removed to obtain access to the interior of the casing 12, and may be rewelded several times, thereby permitting re-use of the casing members. An inverted cup-shaped frame member 18, on which the motor 13 and compressor 14 are entirely assembled in vertical relation, provides a vertically-extending bearing 19 and a thrust bearing 20 for

a drive shaft 21 between the motor and compressor.

The motor 13 includes a rotor 22 connected to a hub 23, which is in turn pressed on the drive shaft 21, so that rotational movement is imparted to the drive shaft 21 when the rotor 22 is turned. The frame member 18 is provided with an extended annular sleeve portion 24 into which a stator 25 for the motor 13 is pressed. The stator 25 is energized from a suitable source of electrical energy, which is conveyed into the sealed casing 12 through conductors 26.

The cup-shaped frame member 18 is provided with an opening 30 in its upper closed end 27 and an eccentric bushing 28 is inserted therein. The compressor 14 includes a cylinder 29, and a pin 31 formed integrally with the cylinder 29 and extending into the eccentric bushing 28. By rotating the eccentric bushing 28, the position of the cylinder 29 is varied so that compressor head clearance may be adjusted. Such a construction is fully described and claimed in Patent No. 1,951,558 issued to Carl F. Nystrom and assigned to the Westinghouse Electric & Manufacturing Company. The compressor 14 also includes a 25 crank pin 32 and a counterweight 33 attached to the drive shaft 21. A connecting rod 34 is attached to the crank pin 32 and the other end of the connecting rod pivotally connects with a compressor piston 35, so that the piston 35 is reciprocated in the cylinder 29. A cylinder head 36 is provided for the compressor 14 and contains suitable inlet and discharge valves (not shown).

It is desirable to have low pressure refrigerant gas prevail in the casing 12 because the low pressure, in conjunction, with the operating temperature, results in maintaining the lubricant relatively pure, especially if a refrigerant and lubricant are utilized which are substantially miscible. Gas to be compressed is, therefore, admitted to 40 the interior of the casing 12 through a conduit 31, and is admitted to the cylinder 29 through an inlet conduit 38, which connects to a double muffler chamber 41 of a muffler 42. A conduit 43 is provided in the muffler chamber 41 for withdrawing 45 gas from the interior of the casing 12. Compressed gas is conveyed through a muffler chamber 44 by a conduit 45 and then to the exterior of the casing 12 through a conduit 46 extending from the muffler 42 through the casing 12. The muffler 42 is preferably welded to the frame member 18. The construction and operation of the muffler is fully described and claimed in the copending application of Elliott E. Grover, S. N. 754,967, filed November 27, 1934 for Muffling device and assigned to the Westinghouse Electric & Manufacturing Company. A magnetic unloader 47 is also provided for unloading the compressor at starting, and is connected to the compressor 13 and supported thereby.

A sheet metal cap 52 is attached to the bottom of the cup-shaped frame member 18, and closes the open end thereof, thus forming a closed chamber 53 for the motor 13. A centrifugal impeller type lubricant pump 48 is attached to the end of the drive shaft 21 which extends through the cap 52. An inlet 49 for the lubricant pump 48 extends into a reservoir of lubricant 51 in the bottom of the sealed casing 12. A flanged opening 54 is provided in the bottom of the cap 52 and affords communication between the motor chamber 53 and the interior of the sealed casing 12. Two other openings 50 are provided in the bottom of the cap 52 and provide communication between the lubricant pump chamber formed by housing 55 and the motor chamber 53. A sheet metal housing 55 for the lubricant pump 48 is attached to the cap 52 and forms a volute 56 for the pump 48. An outlet conduit 57 for lubricant extends upwardly from the volute 55. A lubricant dam formed by a sheet metal collar 58 surrounds the flanged opening 54 in the cap 52 and is attached to the cap 52 interiorly thereof for a purpose hereinafter described.

A suspension and buffer ring 59 is disposed around the frame member 18 intermediate of the vertical extent of the sleeve 24 and is attached thereto by brackets 61 of different sizes to provide a space adjacent the larger bracket for the unloader 47, muffler 42 and compressor 14 as well as for the piping connections between the compressor 14 and the muffler 42. The ring 59 is provided with openings 62 spaced 120° apart. Ears 64 provided with openings 64a are fastened to the interior of the upper casing member 15 and are also spaced 120° apart. Suspension springs 63, three in number, are connected between the openings 64a in the ears 64 and the openings 62 in the ring 59 thus providing a jointed three point spring suspension for the motor compressor unit interiorly of the casing 12. The spring suspension damps vibrations and noise due to operation of the motor and compressor and ensures quiet operation. Suspension springs attached to ring 59 and ears 64 by jointed connections are utilized so that no rigid connections are present between the casing 12 and the frame 18 and the horizontal component of vibration is, therefore, eliminated. The ends of the springs 63 are provided with hooked extensions which enter the openings 64a of the ears 64 and the openings 62 of the ring 59. A plurality of flexible clamps 60, provided with a nut and bolt 60a to permit the ring 59 to be slid into the clamps 60, are spot-welded interiorly of the casing 12 and encompass the ring 59 to prevent contact of the ring 59 with the casing 12 and to prevent abnormal movement of the frame 18 in the casing. The entire assembly on the frame member 18, including the motor 13 and compressor 14, is, therefore, resiliently suspended from the upper bell-shaped casing member 15.

In order to cool and lubricate the motor and compressor of a hermetically-sealed internally spring mounted unit, it is essential that a copious quantity of lubricant be circulated in contact with the sealed casing to cool the lubricant and also in contact with portions of the motor-compressor unit to abstract heat therefrom.

76 Referring now to the lubrication and cooling
of the motor-compressor unit, lubricant is with-
drawn from the reservoir 51 by the lubricant
pump 48 through the inlet 49, and is discharged
77 through the volute 56 and outlet conduit 57. The

outlet conduit 57 extends through an aperture 55 in a lubricant distributing plate 66 at the top of the casing 12. The lubricant plate 66, shown in detail in Fig. 5, is inserted in the upper cup-shaped portion of the casing 15 and is supported on the ears 64. Some of the lubricant which strikes the top of the casing 12 drops back through the aperture 65, while other portions of the lubricant pass through aperture 68 in the central portion of the distributing plate 66. The 10 lubricant which drops through the apertures 65 and 68 in the distributing plate 66 is caught by a lubricant pan 69 which is fastened to the compressor 14 and frame member 18 by bolts 71. The lubricant pan 69 is provided with two apertures 15 72 above the head 36 of the compressor, a third aperture 73 above the piston 35 of the compressor 14, and another aperture 74 at the edge of the pan 69. Lubricant caught by the pan 69, therefore, passes through aperture 72 and over the 20 head 36 of the compressor 14 to cool the same. The lubricant pan 69 is larger than the counterweight 33 so that lubricant will not drop thereon, thereby preventing noise from lubricant thrown off the counterweight. A second lubricant 25 pan 75 is disposed below the compressor 14 and collects the lubricant which bathes the compressor head 36. Lubricant caught by the lower pan 75 is directed over the top of the frame member 18, which frame member is provided with a 30 raised lip 76 about its edge to retain a shallow body of lubricant on the top thereof so that heat will be transmitted from the top of the frame member 18 to the lubricant. Lubricant passing through the outer aperture 74 in the upper lubricant pan 69 also drains to the top of the frame member 18 through a passageway 77. A baffle 78 is disposed at the bottom of the passageway 77 to direct the lubricant from the passageway 77 over the top of the frame member 18. Lubricant 40 which passes through the aperture 78 drops on the piston 35 as it reciprocates and is collected in oil grooves 79 in the piston 35, thus lubricating the piston. Any excess lubricant not picked up by the grooves 79 also falls to the top of the frame 45 18. All the lubricant which falls on the top of the frame 18 runs down the sides thereof and over the extended sleeve member 24, thus cooling the motor and frame, and then drops into the reservoir 51.

The remainder of the lubricant conveyed to the lubricant distributing plate 66 is distributed in a film over the interior of the casing 12 through a plurality of apertures 81 in the edge of the lubricant distributing plate 66. This lubricant is cooled by contact with the heat dissipating surfaces of the casing 12 above the lubricant reservoir 51 and is then returned to the reservoir, thus maintaining the lubricant in the reservoir at a relatively low temperature to abstract heat from the motor 13, compressor 14, and frame 18 when portions of the lubricant from the reservoir 51 come in contact therewith.

Lubricant for the bearings of the motor 13 and compressor 14 is conveyed through a conduit 80 which connects with the lubricant outlet conduit 57. Lubricant is conveyed through a passageway 82 to the shaft bearings 19 and 20. Lubricant which is forced upwardly through the passageway 82 also is conveyed to a passageway 83, 84 to lubricate the crank pin 32. Some of the lubricant escaping from the crank pin 32 is thrown into the interior of the piston 29 to cool the same. Lubricant which is forced downwardly flows through a transverse passage 85 in the frame 12, 75

and then through passageways 86 in the rotor hub 23. Lubricant escaping from the passageways 86 is returned to the reservoir through the flanged opening 54 in the motor cap 52. The flange around the opening 54 is of such height to ensure a level of lubricant in pump housing 55 and in cap 52 within the dam 58 sufficient to maintain the lubricant pump 48 primed. The disadvantage of a positive displacement pump is, that, when sudden lowering of pressure occurs on a mixture of lubricant and refrigerant, foaming occurs, the positive displacement pump pumps foam, and insufficient lubrication results. However, liquid lubricant or a mixture of refrigerant and lubricant is always present in a primed pump such as the one disclosed.

As best shown in Figs. 2 and 4, lubricant is also directed from the volute 56 of the pump 48 through the two apertures 50 in the cap 52, thus flooding the lower end of the motor stator 25 with lubricant to cool the same. The level of lubricant on the stator (see Fig. 1) is maintained by the lubricant dam 58, and overflow is returned to the reservoir through flanged opening 54.

The mounting of the motor-compressor unit in the upper casing member 15 with the lubricant baffle 66 and lubricant conduit 57 in proper position, permits testing and running in of the motor compressor unit in an oil bath without the bottom portion 16 of the casing 12 being attached to the upper portion 15 of the casing. The lubrication system and other parts of the apparatus may, therefore, be fully tested and inspected with the lubricant baffle, motor, compressor and lubricant pump in proper assembled relation before the casing 12 is hermetically sealed.

From the foregoing it will be apparent that I have provided an improved hermetically sealed motor-compressor unit which is quiet and efficient in operation and which is susceptible of test in assembled relation before sealing. Furthermore, I have provided a novel and effective cooling and lubricating system for an internally sprung mounted hermetically sealed motor-compressor unit.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. In compression apparatus, the combination of a compressor, a motor for driving the compressor, a hermetically sealed casing for enclosing the motor and compressor embodying upper and lower separably attached portions, a lubricant reservoir in the bottom of the casing, a lubricant distributing means supported by and adjacent the top of the casing, means supported by the upper casing portion for conveying lubricant from the reservoir to the distributing means, and means for resiliently supporting the motor and compressor from the upper casing portion, whereby the motor, compressor, upper casing portion, lubricant conveying means and lubricant distributing means may be completely assembled before attaching the lower portion of the casing.

2. In compression apparatus, the combination of a compressor, a motor for driving the compressor, a frame member upon which the motor and compressor are entirely assembled in vertical superposed relation, a hermetically sealed casing for enclosing the motor, compressor and frame member, resilient means attached to the top of the casing by a jointed connection and extending downwardly therefrom, a ring attached to the frame member, a jointed connection between the resilient means and said ring, whereby said motor, compressor and frame member are resiliently suspended in the casing, and means attached to the casing and encompassing the ring for limiting the movement of the frame member and for maintaining the ring out of contact with the casing.

3. In compression apparatus, the combination of a compressor, a motor for driving the compressor embodying a stator and a rotor, a frame member upon which the motor and compressor are entirely assembled, a hermetically-sealed casing for enclosing the motor and compressor and the frame member, a reservoir of lubricant in the bottom of the casing, a first fixed baffle member in the upper portion of the casing, a second fixed baffle member disposed above the frame member and the compressor, a lubricant circulating pump disposed within the casing for circulating lubricant to the first fixed baffle member, and means embodied in the first fixed baffle member for directing lubricant over the walls of the sealed casing to cool the lubricant before the cooled lubricant is returned to the reservoir, said pump directing other lubricant from the reservoir to the second fixed baffle member and said second fixed baffle member embodying means for directing lubricant therefrom over said compressor and frame member to abstract heat therefrom, said frame member totally enclosing the stator and rotor of said motor to prevent lubricant from contacting with the upper portions of the stator and rotor and said frame member having openings in the bottom thereof to afford passage of the lubricant into contact with the lower portions of the motor stator to abstract heat therefrom before return of lubricant to the reservoir.

4. The combination as claimed in claim 3 wherein the frame member with the motor and compressor supported thereon is resiliently suspended in spaced relation with the interior of the sealed casing.

5. In compression apparatus, the combination of a compressor, a motor for driving the compressor, a frame member upon which the motor and the compressor are entirely assembled in vertical superposed relation, a hermetically sealed casing for enclosing the motor, compressor and frame member, resilient means attached to the top of the casing by a jointed connection and extending downwardly therefrom, attaching means connected to the frame member, a jointed connection between the resilient means and said attaching means, whereby said motor, compressor and frame member are resiliently suspended in the casing, and means associated with the casing and encompassing the attaching means for limiting the movement of the frame member and for maintaining the attaching means out of contact with the casing.

MARTIN G. SATEREN.
